Primary Examiner — Ian Simmons*Assistant Examiner* — Altaira J Swangin(74) *Attorney, Agent, or Firm* — McDermott Will & Emery LLP(57) **CLAIM**

I claim the ornamental design for a pen light with knurled segments, as shown and described.

DESCRIPTION

FIG. 1 is a top perspective view of a pen light with knurled segments according to a new design.

FIG. 2 is a right side view of the pen light shown in FIG. 1.

FIG. 3 is a left side view of the pen light shown in FIG. 1

FIG. 4 is a front view of the pen light shown in FIG. 1.

FIG. 5 is a rear view of the pen light shown in FIG. 1.

FIG. 6 is a top view of the pen light shown in FIG. 1; and,

FIG. 7 is a bottom view of the pen light shown in FIG. 1.

Features shown in broken lines in the drawings represent unclaimed portions of the design. The use of a separation break within a lower handle portion of the pen light in FIGS. 1-7 indicates that any portion of the article between the break lines not shown forms no part of the claimed design.
